OVERHEAD ACTING DOOR

Milton L. Cornell, New York, and Rowland K. Bennett, Staten Island, N. Y., assignors to Cornell Iron Works, Inc., Long Island City, N. Y., a corporation of New York

Application April 12, 1935, Serial No. 15,991

12 Claims.

(Cl. 20—19)

This invention relates to overhead acting doors of the rigid single panel or "canopy" type.

A general object of the invention is to provide such a door having improved features of design affording a better closure and one that operates and functions in a manner superior to that obtainable with presently available doors of this type.

More specifically, objects of the invention are to provide a canopy door having an improved form of weather stripping which assures a tight closure at the sides of the door without interfering with its operation, or encroaching on the door opening when the door is raised, together with improved means for effecting and controlling such door operation.

A further object of the invention is to provide improved means for opening and closing such a door, as well as for positively retaining it in either its open or closed position.

Another object of the invention is to provide means for braking or slowly arresting the opening movement of the door so that it will not be forced or pulled by its counterweight to its open overhead position in a too forceful and destructive manner.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a fragmentary contracted view of a door and its associated appurtenances constructed in accordance with the principles of the present invention;

Fig. 2 is a vertical sectional view taken along line 2—2 of Fig. 1;

Fig. 3 is a fragmentary vertical sectional view on an enlarged scale corresponding substantially to line 3—3 of Fig. 1, parts thereof being broken away better to show the construction;

Fig. 4 is a fragmentary vertical sectional view substantially corresponding to Fig. 3 but showing the door in its open overhead position;

Fig. 5 is a fragmentary horizontal sectional view taken along line 5—5 of Fig. 1, on a scale corresponding to that of Figs. 3 and 4;

Fig. 6 is a horizontal sectional view, on a further enlarged scale, taken along lines 6—6 of Fig. 1;

Fig. 7 is a fragmentary elevation of the upper right hand corner of the door shown in Fig. 1, parts being broken away better to show the construction; and

Fig. 8 is a fragmentary perspective view, on an enlarged scale, of the upper right hand corner of the door per se, particularly showing the weather stripping structure.

Referring more particularly to the drawings, there is shown in Fig. 1 a canopy door 10 comprising a flat nonarticulated rigid panel which is adapted to cover the entire door opening defined by the jambs 11, sill 12, and lintel 13. These parts may be of any suitable, approved design. In the present illustrative embodiment, the jambs 11 are preferably formed of angle iron (Figs. 5 and 6) extending from top to bottom of the door opening and attached in any suitable manner to the wall 14 of the building. A dressed timber, or any other suitably smooth surfaced member, may be substituted for the angle iron.

At its upper portion the door has at each side edge a bracket 15 to which is pivotally attached a supporting strap 16 which in turn is pivotally suspended at 17 from its associated jamb 11, or from any other suitable supporting bracket on the building. The arrangement of these parts is such that when the door is in its closed vertical position, it may hang from straps 16 and have all or any desired part of its weight supported thereby, thus rendering unnecessary any heavy or binding bearing contact between the bottom roll of the door and the sill 12. A further function of these straps is to guide the upper part of the door outwardly when raised.

The door is additionally provided at each side edge with brackets 18 which are vertically located at about the balance point thereof. These brackets each are provided with a bearing 19 in which the shaft of a guiding roller 20, best shown in Figs. 5 and 7, is mounted. The guiding rollers 20 at each side of the door are respectively vertically slidable in vertical guides 21 (Figs. 1, 5 and 7). Doors of this type are counterweighted or counter sprung, as for example in the manner hereinafter to be described, so that upon opening they heretofore have shown a tendency to acquire considerable upward momentum, which when suddenly arrested through contact of the door with the lintel 13, causes destructive stresses to be applied to the door structure. In accordance with the present invention, this is avoided

by making the guides 21 in the form of channel irons having one sloping side web 22 (Fig. 5) so that the interior width of the guiding channel, from front to back, is somewhat less than the 5 diameter of the roller 20 at the channel's least dimension, but is sufficient in its wider portions freely to accommodate this roller. The entire channel is fastened in any suitable manner to an angle iron 23 which is in turn fixed to the jamb 10 11. Each guiding channel 21 adjacent its upper end is distorted as by bending inwardly at 24 (Figs. 1 and 7) for a distance d (Fig. 7) sufficient to cause the converging sidewalls of the channel to close upon and slightly bind the roller 20 15 during the last portion of its upward movement. There is sufficient resilience in the metal parts employed such as the channel 21 and, if desired, the support 23, to brake or retard the opening movement of the door without absolutely binding 20 the roller 20, thus assuring an easy, cushioned stop. Instead of bending in the upper portions of guide channels 21, the portions 22 may be bent outwardly to bind the roller 20 more 25 closely as the limit of its travel approaches or the entire channel may be mounted slightly out of plumb so as to have the desired wedging effect at its upper end. Also, the downward closing movement of the door may be braked by similar distortion of guides 21, if desired, so that both 30 movements of the door may be cushioned.

A collar 25, best shown in Fig. 7, is fitted over the shaft of roller 20 at each side of the door, and from these respective collars cable sections 26 and 27 are run to a counterweight 28. The cable section 26 runs over sheaves 29 and 30 (Figs. 1 and 3) and the cable section 27 runs over a sheave 31 being led downwardly from sheaves 30 and 31 to a cable length compensating device generally indicated at 32 (Fig. 7). This device 40 comprises a pair of spaced plates 33, only the forward one of which is visible in the illustration, which are joined by pins 34 and 35 around which the respective cable sections 26 and 27 are passed and between which these sections are pulled up 45 to form a bight 36, which is held clamped against slippage by suitable screw joined clamping plates such as 37. The counterweight 28 may preferably comprise a plurality of sections hung on a strap 38 which is pivotally suspended from a pin 50 39 joining the plates 33. This construction allows the plates 33 to tilt one way or the other in order to compensate for slight differences in the relative lengths of cable sections 26 and 27, so that an equalized counter balancing force will be 55 applied to the respective brackets 18 at each side of the door, at all times.

It will be understood that if desired, any conventional or suitable form of spring counterbalance may be employed in lieu of the weight 60 arrangement shown, and the term "counterbalance" as herein used, is intended to apply to either spring or weight types of equipment.

In view of the fact that an equalized counterbalancing at both sides of the door is provided, it is possible to operate the door from one side or the other without having it bind. In accordance with the present illustrative showing of the invention, the door is operated from the right side as viewed in Fig. 1 by means of a rigid operating strap 40 which is formed of metal and is suspended from the bearing 19 at the right side of the door by means of a loose motion slot 41 (Fig. 3). This strap is so located along the bearing that it hangs to the right of the jamb angle 75 iron 11 as viewed, for example, in Fig. 7. A

bracket 42 having an open ended slot is affixed to the outer face of the door adjacent the lower end of strap 40, and a pin 43 affixed to this strap projects toward and is adapted to seat within the open ended slot in bracket 42 when the door is 5 in its completely closed position. At such time the pin 43 spans the edge 44 (Fig. 6) of the jamb 11 so that any tendency to swing the bottom of the door inwardly is arrested through abutment of this pin against the jamb. This prevents unintentional opening of the door through inadvertent application of forces to the body of the door tending to swing its lower part inwardly or its top part outwardly. On the other hand, when it is desired to tilt and raise the door to its open 10 position, this can be done by grasping a forwardly extending handle portion 45 of the strap 40 and bodily lifting the strap until the loose motion at 41 is taken up, at which time the pin 43 will clear the bracket 42 so that the door is free to swing 15 inwardly away from such pin. This construction may be modified by omitting the slot in strap 40, and instead mounting the bracket 42 so that it may be moved vertically to clear pin 43 by a cylinder lock, handle or other means on the door. 20 Continued upward movement of the strap 40 applies an upward force to the bearing 19, thus elevating the door, which by virtue of its suspension from straps 16 tends to swing about the axis of bearing 18 so as to adopt the horizontal 25 overhead position shown in Fig. 4.

In order to prevent undesired lowering of the door, a supporting ledge 46 (Fig. 4) is mounted on the door jamb in position to underlie and support a heel 47 (Fig. 4) on the strap 40 which later by virtue of its rigidity, prevents descent of the door until such heel is disengaged by pulling outwardly on the handle 45. By means of this construction the door is adapted positively to be held in either its open or closed position against 40 accidental forces, such as wind, weight of snow, etc., which, because of its rather sensitive balance, might otherwise readily tend to cause it to swing to an unwanted position. A further advantage of this operating structure is that the 45 rigidity of the strap 40 makes it possible to continue to apply opening force to the door even after the latter is out of manual reach. Heretofore it has been customary, in manually operated doors of this type, to affix a flexible operating 50 strap or leather or the like centrally of the lower rail. This arrangement, in addition to hanging down in the way when the door is in overhead position, necessitated the use of a pole or the like to complete the opening of the door after it was 55 out of manual reach or else called for a violent opening shove, which, prior to provision of the herein described braking equipment, had noisy and destructive effects. By locating the present operating strap at the side of the door, it is never 60 in the way.

Heretofore, with doors of this type, considerable difficulty has been experienced in providing a properly weather proofed closure, particularly after they have been in service for a while and subjected to warping and curling. In accordance with the present invention, a permanently effective weather proofing is obtained by applying a yieldable outwardly biased weather stripping along the lateral edges of the door between such 70 edges and the jamb. This weather proofing, which is best shown in Figs. 6 and 8, comprises a sheet metal channel 48 having inturned flanges as at 49 between which is slidably telescoped a mating channel 50 having outturned retaining 75

flanges 51. These complementary channels 48 and 50 extend from top to bottom of the door along each lateral edge and the channel 50 is normally spring biased outwardly by means of 5 suitably spaced leaf springs 52. These springs constantly urge the channel 50 into weather tight contact with their adjacent jamb 11. The spring pressure between these parts does not adversely affect the operation of the door, because during 10 most of the opening and closing movement thereof, the channel 50 is in rubbing contact with the jamb 11 only for a short distance adjacent its middle portion, and because there should be provided relatively smooth surfaces in the parts of 15 jamb 11 and channel 50 which are in contact during movement of the door.

The top of the door is made weather tight by means of a resilient upwardly curved strip of metal 53 which is adapted to abut the lintel when 20 the door is in closed position. The holes for attaching part 53 to the door are preferably slotted as shown to allow of adjustment against the face of the lintel.

It will be seen that there has been provided a 25 weather proof canopy type door which is capable of generally improved performance and operation, and which is well suited to fulfill its intended functions.

Since certain changes may be made in the 30 above construction and different embodiments of the invention could be made without departing from the scope thereof, it is intended that all matter contained in the above description or shown in the accompanying drawings, shall be interpreted as illustrative and not in a limiting sense.

It is also to be understood that the following 35 claims are intended to cover all of the generic and specific features of the invention herein described, and all statements of the scope of the invention which, as a matter of language, might be said to fall therebetween.

Having described our invention, what we claim as new and desire to secure by Letters Patent, is:

1. A canopy type overhead acting door 45 comprising a door body, means suspending said door for movement between closed and open positions, elongate guideways along which said door is movable, said guideways being arranged frictionally to retard said door as it ends one of said movements.

2. A canopy type overhead acting door comprising a door body, means suspending said door for movement between closed and open positions, 50 an element projecting from said door, an elongate guideway limiting movement of said element to a linear path, said guideway being arranged frictionally to retard said element as said door ends one of said movements.

3. A canopy type overhead acting door comprising a door body, means suspending said door for movement between closed and open positions, an element projecting from each side of said door, a guideway for each of said elements, said guideways being distorted at their upper ends frictionally to engage and retard said elements as the door is opened.

4. A canopy type overhead acting door comprising a door body, elements projecting from 55 opposite sides of said door body, counterbalancing means, cables connecting said means and said elements, and guideways for said elements, said guideways being distorted at their upper ends frictionally to engage and retard said elements 60 as the door is opened.

5. A canopy type overhead acting door comprising a doorway, a door body, a counterbalance, means suspending said door from said counterbalance for vertical movement between closed and open positions, link means between 5 said door and doorway compelling said door to turn about a horizontal axis as it ascends and descends, elongate guide means holding said axis in a fixed rectilinear path, said guide means being arranged frictionally to retard said door as it approaches one of said positions.

6. A canopy type overhead acting door comprising a door body, means suspending said door for movement between closed and open positions, a rigid operating strap for manually operating 15 said door having one end pivotally attached thereto and having its other end free, and means for supporting the free end of said strap to prevent unintentional lowering of said door when it is in open position.

7. A canopy type overhead acting door comprising a door body, means suspending said door for vertical movement between closed and open positions, means forcing said door to turn about one of its horizontal axes during such vertical movement, a rigid strap for manually operating said door having one end pivotally attached thereto and having its other end free, and locking means associated with said strap and an adjacent door frame for preventing said door from 20 turning about said horizontal axis.

8. A canopy type overhead acting door comprising a door jamb, a door body, means suspending said door body for vertical movement between closed and open positions, means forcing said door body to turn about one of its horizontal axes during such vertical movement, a rigid strap pivotally suspended from one side of said door for loose motion with respect thereto, a pin projecting from said strap toward said door and spanning said jamb, and a slotted bracket on said door adapted to receive said pin when said door and said strap are both in their lowermost positions, said pin being removable from said bracket upon taking up the loose motion 30 between said strap and door.

9. A canopy type overhead acting door comprising a door body, a door opening including laterally spaced jambs having flat unobstructed surfaces substantially parallel with the lateral edges of said door body, said surfaces extending over all portions of the jamb which are opposed to said edges during operation of the door, means suspending said door body for vertical movement between said jambs, means for turning said door body about one of its horizontal axes during such vertical movement, and weather stripping means located on said door between the lateral edges of said door and their adjacent jambs for rubbing contact with the latter.

10. A canopy type overhead acting door comprising a door body, a door opening including laterally spaced jambs having flat unobstructed surfaces substantially parallel with the lateral edges of said door body, said surfaces extending over all portions of the jamb which are opposed to said edges during operation of the door, means suspending said door body for vertical movement between said jambs, means for turning said door body about one of its horizontal axes during such vertical movement, and spring biased, expandable weather stripping means located on said door between the lateral edges of said door and their adjacent jambs, the portions of said weather stripping means adjoining said axis being 65 70 75

ing in constant rubbing contact with and laterally confined by said jambs.

11. A canopy type overhead acting door comprising a door body, a door opening including laterally spaced jambs having flat unobstructed surfaces substantially parallel with the lateral edges of said door body, said surfaces extending over all portions of the jamb which are opposed to said edges during operation of the door, means suspending said door body for vertical movement between said jambs, means for turning said door body about one of its horizontal axes during such vertical movement, and spring biased, outwardly expandable weather stripping extending in a continuous strip from top to bottom of each lateral edge of said door toward and in pressing engagement with its adjacent jamb when the door is in closed position and means comprising said jambs for limiting said outward expansion of said weather stripping when the door is in open position.

12. A canopy type overhead acting door com-

prising a door body, a door opening including laterally spaced jambs having flat unobstructed surfaces substantially parallel with the lateral edges of said door body, said surfaces extending over all portions of the jamb which are opposed to said edges during operation of the door, means suspending said door body for vertical movement between said jambs, means for turning said door body about one of its horizontal axes during such vertical movement, weather stripping including an outwardly movable strip mounted on and interlocked with said door body, said strip being located between the lateral edges of said door body and their adjacent jambs and extending from top to bottom of the door body, and spring means urging each movable strip into contact with its adjacent jamb when the door is in closed position, each strip being adapted to slide freely upon its adjacent jamb during movement of the door.
